UNITED STATES PATENT OFFICE.

ISAAC LEVIN, OF NEW YORK, N. Y.

GARMENT-FORM.

1,039,763.

Specification of Letters Patent.

Patented Oct. 1, 1912.

Application filed December 30, 1911. Serial No. 668,705.

To all whom it may concern:

Be it known that I, ISAAC LEVIN, a citizen of the United States of America, residing at 5 borough of Brooklyn, county of Kings, city and State of New York, have invented certain new and useful Improvements in Garment-Forms, of which the following is a full, clear, and exact description.

This invention relates to improvements in 10 garment forms, but more particularly to the skirt portion thereof, and means for releasably securing the same to the bust portion of the form.

One of the objects of my invention is to 15 provide a garment form which can be packed into a comparatively small space when not in use or when shipped.

A further object of my invention is to provide an adjustable skirt portion which can 20 be attached to bust-forms of different sizes, that is to say, of various hip and bust measurements.

A still further object of my invention is to 25 provide a skirt portion which is more durable than those now in use and less liable to be injured or crushed. The skirt portions of the garment forms now in use are generally made out of round wire, and during 30 shipment or manipulation by tailors and others, these skirt portions become bent and knocked out of shape. To overcome this objection, I preferably make my improved skirt portion out of flat spring metal strips, and secure the members, which go to form 35 the said skirt portion together by means of eyelets. To solder the members of a skirt portion together is objectionable, for the reason that the soldered connections tend to break. To solder spring metal together is 40 difficult, if not impossible, and I find eyelets to be the cheapest method of securement, as an ordinary eyeleting machine can be utilized.

I will now proceed to describe my invention, in detail, the novel features of which 45 will be pointed out in the appended claim, reference being had to the accompanying drawings, forming part hereof, wherein:

Figure 1 is a side elevation of my improved garment form; Fig. 2 is a sectional view partly in elevation of my improved garment form, the skirt portion being removed; Fig. 3 illustrates, in side elevation, my improved garment form ready for shipment or storage; Fig. 4 is an enlarged detail view of my improved skirt portion

spread open; Fig. 5 is a top edge view thereof; and Fig. 6 is a detail perspective view of the securing device for the skirt portion.

Referring to the drawings my improved garment form comprises the bust-portion 1, the skirt portion 2 and support 4, the latter consisting of the tubular member 5 and rods 6 and 7, which are detachably connected together or joined, as at 8. A suitable base 65 portion 9, upon which the form rests is secured to the tubular member 5. To render the skirt portion 2 practically indestructible, I make the same out of flat resilient metal strips, the members 10 being the band members, which are connected together by the vertical members 11, 11^a. The members 10, 11 and 11^a are secured together by means of eyelets 12 (see Fig. 4).

As has been stated, one of the objects of my invention is to render the skirt portion 75 adjustable; in other words, to adapt it to fit bust-forms of different dimensions. To render the skirt portion adjustable in this respect, I provide one end of the band members 10 with buttons or catches 13, and the other end of the said band members 10 with slots 14 adapted to receive and hold the buttons 13, whereby the skirt portion is maintained in a circular form.

As can be seen in Fig. 4, I provide a plurality of buttons 13 and a plurality of slots 14, by which means the skirt portion can be increased or decreased in diameter within certain limits. To obtain a greater arrangement of adjustment, I preferably divide the skirt portion (in this instance) into two sections 15 and 16 and connect the sections by means of toggle connections 17. It is quite obvious that the sections 15 and 16 can be 95 brought together or spread apart by means of the said toggles 17.

To attach the skirt portion to the bust portions, I provide the upper end of each of the vertical members 11^a with a slot 18, 100 which is adapted to receive and hold a button 19 carried by a pivotally mounted plate 20, the said plate being carried by the bust-portion of the form, as shown in Figs. 1 and 2. The object of pivotally mounting the 105 plates 20 is to adapt them to be shifted to meet the slots 18 in the vertical members 11^a, should the diameter of the skirt portion be changed.

The advantage of the demountable skirt 110 portion is that it can be applied to various forms. For instance, a tailor or dressmaker

might have a number of bust portions of different hip dimensions, but it would be necessary to have but one skirt portion, it being understood that all of the bust-forms would be fitted with the securing plates 20.

To render the garment form a knock down structure, I make the support 4 as shown in Fig. 2. In other words, the rods 6 and 7 are screw-threaded on their adjacent ends and are held together by a coupling 21. The rod 6 is permanently fixed in the bust-portion of the form and the coupling 21 can be secured to the header 22^a. As can be seen in Fig. 2, the rod 7 can slide within the tubular member 5 and can be held in an adjusted position by means of the binding screw 23^a.

When the form is to be stored or shipped, the rod 7 will be taken out of the member 5 and unscrewed from the coupling 21. The skirt portion will be removed from the bust portion by moving it upward until the buttons 19 align with the openings 22, which communicate with the slots 18 at which time the vertical members 11^a can be sprung outwardly and away from the buttons. When thus disconnected, the skirt-portion can be moved upwardly over the bust portion to the position shown in Fig. 3. It will be quite apparent that when the support 4 for the garment forms is disconnected, as described, and when the skirt portion is disconnected from the bust form, the structure will occupy but a comparatively small space.

As the members 10, 11 and 11^a are spring members, being tempered to form such members, the skirt portion 2 will go flat as soon as the connection at 23 (Fig. 1) is broken. In other words, when not in position upon a

bust portion of a garment form, the skirt 40 portion will be flat, as shown in Fig. 4. For the purposes of shipment, this is of great value. Should I desire to ship a number of skirt portions, I can lay one upon the other 45 and ship them flat, which not only is a protection against breakage or disfigurement, but also renders them more easily handled. My improved skirt portion is manufactured flat and is bent around the bust form when in use. By making the skirt portion out of 50 flat spring metal strips, the structure is adapted to give under pressure and to spring back into shape when the pressure is removed. This is not the case with the skirt portions now in use, which are made out of 55 wire or untempered metal. A further advantage of my improved skirt portion is that the diameter of the bottom can be changed without changing the diameter of the top. This feature is quite obvious and is advantageous for the purpose of hanging skirts of different bottom dimensions, but of the same hip dimensions.

Having now described my invention, what I claim and desire to secure by Letters Patent is:

In a garment form, a bust portion, an adjustable skirt portion, plates pivotally secured, at one end thereof, to said bust portion, and means carried by said plates adapted to releasably engage said skirt portion.

Signed at New York city, N. Y., this 29th day of December 1911,

ISAAC LEVIN.
